UNITED STATES PATENT OFFICE

90,747

DESIGN FOR A PILLOW OR SIMILAR ARTICLE

Edward J. Barcalo, Buffalo, N. Y., assignor to
Six-Way Corporation, Buffalo, N. Y., a corpora-
tion of New York

Application June 3, 1932. Serial No. 43,969

Term of patent 14 years

To all whom it may concern:

Be it known that I, EDWARD J. BARCALO, a citizen of the United States, residing at Buffalo, Erie County, State of New York, have invented a new, original, and ornamental Design for a Pillow or Similar Article, of which the following is a specification, reference being had to the accompanying drawing forming a part thereof.

In said drawing:

Fig. 1 is a perspective view of a pillow or similar article embodying my design.

Fig. 2 is an end view thereof.

The pillow has opposite substantially parallel ends each of substantially triangular outline, and side faces extending from one to the other of

the ends and each of which is crowned or convexed and of substantially rectangular outline, so that the pillow, when viewed from either end is substantially triangular in shape and when viewed from any side is substantially rectangular in shape. Also, while the several sides of the pillow are of different breadths, the narrowest side is of substantial breadth as compared with the broadest side so that the pillow will have substantial elevation when resting on any one of its sides.

I claim:

The ornamental design for a pillow or similar article, substantially as shown and described.

EDWARD J. BARCALO.
